UNITED STATES PATENT OFFICE.

JOHN T. DONNELL, OF ST. LOUIS, MISSOURI.

DESIGN FOR A SOUVENIR SPOON, FORK, OR SIMILAR ARTICLE.

SPECIFICATION forming part of Design No. 35,923, dated May 27, 1902.

Application filed December 7, 1901. Serial No. 85,112. Term of patent 3½ years.

To all whom it may concern:

Be it known that I, JOHN T. DONNELL, a citizen of the United States, and a resident of St. Louis, Missouri, have invented and produced a new and original Design for Souvenir Spoons, Forks, or Similar Articles, of which the following is a specification, reference being made to the accompanying drawings, forming part thereof.

10 Figure 1 is a plan view of a souvenir-spoon, showing my new design. Fig. 2 shows the reverse side of the spoon. Fig. 3 is an edge view thereof.

15 The design, as shown in the drawings, consists, essentially, of a handle for a spoon, fork, or other table utensil, being formed of a shank 1, which is of a gradual taper from its point of connection with the bowl toward the handle end, near each end being ornamented by

a foliated design 2, that at the end farthest 20 from the bowl being surmounted by a pagoda-like ornamentation, the roof or upper inclined portion of which is in representation of lattice-work and which in turn is surmounted by a lattice-work globe 3, upon the extreme 25 end of which is a cupola, as shown. The shank portion is beaded centrally from its middle foliated design to that adjacent the bowl. The back of the handle design is flat and without ornamentation. 30

I claim—

The design for a souvenir spoon, fork, or similar article, substantially as herein shown and described.

JOHN T. DONNELL.
